UNITED STATES PATENT OFFICE.

HENRY RALL, OF ST. LOUIS, MISSOURI.

LARD AND OIL TANK.

SPECIFICATION forming part of Letters Patent No. 291,535, dated January 8, 1884.

Application filed February 19, 1883. (No model.)

To all whom it may concern:

Be it known that I, HENRY RALL, of St. Louis, Missouri, have made a new and useful Improvement in Lard and Oil Tanks, of which 5 the following is a full, clear, and exact description, reference being had to the annexed drawings, making part of this specification, in which—

Figure 1 is a central vertical section of the 10 improved tank, and Figs. 2 to 5 details upon an enlarged scale, Fig. 2 being a vertical section of the lower end of the tank and the parts therewith connected, the upper valve being closed and the lower valve open; Fig. 3, a 15 view similar to that of Fig. 2, both valves being open; Fig. 4, a bottom view of the upper valve, and Fig. 5 a section taken on the line 5 5 of Fig. 2.

The same letters denote the same parts.

20 The present invention relates to an improved mode of constructing the bottom of the tank and the parts immediately therewith connected.

A represents a lard, oil, or other tank in 25 which the present improvement is embodied. Aside from the improvement, the tank is of the usual description.

B represents the chamber in which are placed 30 the articles from which the lard, &c., is prepared. They are supported upon the conical or tapering perforated bottom C and the head or valve D. The shell a of the tank is extended below and around the bottom C, so as 35 to inclose a space, E, beneath and around the perforated bottom C. An opening, F, at the bottom of the tank, is made to be closed, when desired, by the valve G. The valves D and G are attached to the rod H, as follows: The 40 valve G is fastened to the rod, and this valve and rod always move together, whether the rod is lifted or lowered. The upper valve, D, is upheld by means of the shoulder h on the rod H—that is, the valve D opens downward by dropping the rod H; but as it is necessary 45 to the operation of the improved tank to be able to drop the lower valve, G, without at the same time necessarily dropping the upper valve, the upper valve can be upheld and the opening e in the bottom C kept closed 50 when the rod and lower valve are lowered,

and as follows: The upper valve is provided with lugs d d, which, when the valve is suitably turned around, come above projections i i, which are attached to the bottom C, and as long as the valve is thus turned it is upheld 55 in the opening e; but the valve D being loose on the rod H, the rod can be dropped through the valve D, as shown in Fig. 2, and the lower valve be opened. On the other hand, when it is desired to open both valves, the rod H is 60 turned around. The rod is squared where it engages with the valve D, and the turning around of the rod causes the valve D to be turned around, and when the valve has been turned sufficiently to bring the lugs d d out 65 of line with the projections i i the valve D can drop with the rod H, and both valves can then be opened, as shown in Fig. 3. To close the valves, the rod is lifted until the valves are seated. The rod is then rotated until the lugs 70 d are above the projections i, as shown in Fig. 1. The lower valve is preferably seated by drawing it upward against the flange i'. The upper valve closes the opening e by being made to fit the wall i'', surrounding the opening e. This wall i'' is extended upward and downward, substantially as shown, to insure the seating of the upper valve as the packing 75 g of the lower valve wears away. The opening F, in diameter, is larger than the opening 80 e, to provide for the passage of the lugs d d. The parts i i' i'' are preferably in one piece, I, which is fastened to both the bottom C and the shell a, and made to support the bottom C at the center. 85

In operation the tank is filled in the ordinary manner, and the charge rests upon the perforated bottom C and valve D. The steam used in cooking the charge is introduced into the space E, being delivered thereto 90 through the inlet i'', which is conveniently formed in the part I. It is an advantage, also, to have the steam enter the tank at the bottom thereof. By reason of the shape of the space 95 E, the steam can pass upward and enter the chamber B well above the level of the valve D, thus providing a freer access to the charge within the chamber B. In cooking the charge, the usual water of condensation collects in the chamber B, and to be able to readily dispose 100

of it is an aim and advantage of the improvement. By opening the lower valve, G, and keeping the upper valve closed, as in Fig. 2, the water can flow downward through the perforations $c' c'$ in the bottom C and through the opening F without any difficulty arising from the choking of any valve-opening. Heretofore, as lard-tanks have been made, the residue from the tank has been liable to drop and choke the valve-opening when the valve was opened to discharge the water; but in this tank the residue is upheld by the upper valve during the draining of the water. The residue can also be washed in the same manner—that is, after the water of condensation has been withdrawn and the lard drawn off, (which is done in the usual manner, and through the usual cocks in the tank, but which are not shown in the drawings,) water can be introduced into the upper part of the chamber B and allowed to run down through the residue, the openings $c' c'$, the space E, and opening F, and the residue thereby be cleaned. After the residue is ready to be discharged from the chamber B, the upper valve is opened, as well as the lower valve, substantially as shown in Fig. 3, and the residue is discharged through the openings $c' F$. The projections $i i$ on top are slightly beveled, (not shown,) the aim and effect of which is, as the upper valve is turned around to seat it, to cause the valve to be lifted slightly, and sufficiently to cause the valve, when seated, to be supported by the part I, and not by the shoulder h upon the valve-rod. This is desirable to enable the rod to be more readily operated.

The valve D may, to discharge the water of condensation and to admit the steam, have fine perforations, similar to the perforations c' in the bottom C.

I claim—

1. A lard or oil tank having an inner and an outer bottom, each separate from the other, the inner bottom being perforated and the outer bottom being imperforated, and each bottom having for the discharge of the residue an opening in its lower end capable of being closed by a valve, and the valve in the outer bottom capable of being opened and closed independently of the valve in the inner bottom, for the purpose described. 45

2. A lard or oil tank having the perforated tapering bottom C, the valve D, the closed tapering bottom a , independent of the bottom C, and having the valve G and the rod H, substantially as described. 55

3. The combination of the bottom C, the valve D, having the lugs $d d$, the projections $i i$, the bottom a , the valve G, and the rod H, substantially as described. 60

4. The combination of the bottom C, the valve D, having the lugs $d d$, the part I, having the projections $i i$, and the seats $i' i'$, the valve G, and the rod H, substantially as described. 65

5. The combination of the bottom C, the valve D, the lugs $d d$, the projections $i i$, the valve G, and the rod H, said rod being squared to rotate said valve D, and having a shoulder, h , to lift said valve D, substantially as described. 70

6. A lard or oil tank having an inner perforated bottom above the outer bottom, said inner, as well as the outer, bottom also having an opening closed by a valve, for the discharge, when desired, of the residue downward from the tank.

HENRY RALL.
